UNITED STATES PATENT OFFICE.

THOMAS R. BARRABEE, OF LOS ANGELES, CALIFORNIA.

FOLDING BOX.

1,149,805.

Specification of Letters Patent. Patented Aug. 10, 1915.

Application filed October 5, 1914. Serial No. 865,602.

To all whom it may concern:

Be it known that I, THOMAS R. BARRABEE, a citizen of the United States, residing in Los Angeles and State of California, have 5 invented a certain new and useful Improvement in Folding Boxes, of which the following is a specification.

My invention relates to a receptacle of the folding type and designed primarily for 10 conveniently folding and carrying articles of clothing, suits, hats, and the like, an object of this invention being to provide a blank which may be quickly formed into a box, which, when once folded, retains its 15 folded form and on which is provided a convenient carrying grip for the hands.

These and other objects are accomplished by the blank described in the subjoined specification in connection with the accompanying drawing, and then more particularly pointed out in the claim.

In the drawing, Figure 1 is a plan view of the blank, and Fig. 2 is a perspective, illustrating the blank in form of a folded 25 box.

The blank A comprises a bottom 1, having parallel score lines 2 and 3, and sides 4 and 5, foldable at the score lines 2 and 3 respectively at right angles to the bottom 1. 30 On each end of the side 4 are end flaps 6, divided from and foldable at right angles to said side by score lines 7, said flaps 6 being held in such rectangular position at one end by tongues 8, which engage in incisions 9 on 35 the bottom, and at the other end by tongues 10, arranged to engage incisions 11, on the top portion 12, and foldable at the score line 12' on said side 4. The side 4, with its complementary bottom 1, end flaps 6 and top 40 portion 12, forms a rectangular inclosure integrally connected with a telescoping inclosure of which the side 5 constitutes the main part. On each end of said side 5 is a flap 13, divided from and foldable at right 45 angles to said side 5 by score lines 14, these flaps 13 being held in folded position by tongues 15 on said flaps, which engage in incisions 16 in a cover 17, divided from said side by score line 18, and which cover is 50 also held in position by said tongues 15. Centrally of and integral with said cover 17, is a wing 19, formed with a cut-out portion 20, and providing a handle. A similar wing 21, and forming another handle, is cut out

on three sides from said cover 17, the other 55 side being connected with the side 5. Over the portion cut out to form said handle or wing 21, may be glued, riveted or otherwise secured, a suitable reinforcing strip 22, which extends preferably over the score line 60 18 and onto the other side 5.

The aforementioned top portion 12, is provided near the score line 12' with a slot 23 through which is arranged to extend the handle 19, when the blank is folded, as 65 shown in Fig. 2, said handle serving also to hold the box folded. In folded form it will be seen that the cover 17 is immediately below the top portion 12, which latter also adds to the strength of the cover 17, and 70 insures the package against rupture at any point. It will also be seen that where folded as shown, the handle 19 holds the inclosures, formed by the sides 4 and 5, and their complementary parts, in secure telescoped relation, and that, since the two inclosures have 75 a common bottom, dissociation is impossible except at the top. The handles 19 and 21, may have suitable interlocking members 24 for holding together the same, and may also 80 be strengthened in any desired manner, by suitable reinforces.

What I claim is:

A box blank consisting of a single strip 85 of material having a bottom portion provided with incisions and two sides foldable at right angles to said bottom, one of said sides having end flaps, furnished with tongues for locking engagement with the incisions in said bottom, and a top portion 90 provided with a slot; and said other side having a cover provided with incisions, and end flaps having tongues for engagement with the incisions in said cover; said cover having cut therefrom a wing forming a handle and connected at one point to said side, 95 a reinforcement for said cover, and a wing forming a terminal extension of said cover and a handle, said handle being arranged to extend through the slot in said top portion 100 of said first named side.

In testimony whereof I affix my signature in the presence of two witnesses.

THOMAS R. BARRABEE.
